UNITED STATES PATENT OFFICE.

FRITZ HUBER, OF MANNHEIM, GERMANY, ASSIGNOR TO THE FIRM HEINRICH LANZ,
OF MANNHEIM, GERMANY.

FUEL-ADMISSION DEVICE FOR HEAVY-OIL ENGINES.

Application filed April 30, 1921. Serial No. 465,915.

To all whom it may concern:

Be it known that I, FRITZ HUBER, a citizen of the Republic of Germany, residing at Mannheim, Germany, have invented certain new and useful Improvements in Fuel-Admission Devices for Heavy-Oil Engines, of which the following is a specification.

Heavy oil engines in which the fuel on emerging from the nozzle is sprayed by 10 a spirally grooved guide piece inserted in the mouth of the nozzle so as to impart a whirling motion to the fuel, frequently have the disadvantage that they stop under a small load or when running free due to the 15 ignition missing. In such an arrangement the fuel, which is sprayed or vapourized, after emerging from the nozzle forms a cone which, in the form of an annulus encounters an incandescent plate arranged for instance 20 at the wall opposite the nozzle, where it is vapourized, and on the compression being increased is ignited. In the case of a reduced load, the amount of fuel which encounters the incandescent plate is so small 25 that the mixture of fuel and air formed is too poor to ignite.

This invention consists in the arrangement by which, with a decrease in the load, the apex angle of the fuel cone is diminished 30 so that when "idling" or running free this angle is very substantially reduced. The annulus of contact of the fuel with the incandescent plate is thereby reduced and the mass of the fuel is correspondingly denser 35 while the mixture of air and fuel are correspondingly richer, so that even when running free ignition takes place with certainty within the annulus of contact, which is still further ensured by the incandescent plate re- 40 maining hot in the middle longer than at its outer portion.

Incandescent ignition engines are known in which a nozzle in a vapourizing chamber is located opposite an incandescent plate in 45 the centre of which a hot ignition chamber is connected by means of a neck portion. With full load a portion of the mixture of fuel and air is forced into the preliminary ignition chamber where it impinges against 50 the hot walls of the said ignition chamber and ignites whereupon the gas fires back in jets of flame through the said neck portion into the ignition chamber A and ignites the remainder of the mixture of fuel and air, 55 When the engine is running free the core

of the fuel cone is very poor in fuel so that on compression hardly any fuel is forced into the ignition chamber but practically only fresh air, so that ignition in said chamber cannot therefore take place. Now with 60 the device according to the present invention a very rich mixture is forced into the said neck portion during free running in consequence of the small angle of dispersion, and this mixture can still be ignited 65 with certainty even if the walls of the ignition chamber have become cooler than when running on full load.

One form of device according to the present invention is illustrated in the accompanying drawing in which Figure 1 is a sectional view of the cylinder head taken substantially on the line 1-1 of Figure 2, and Figure 2 is a plan view of the cylinder with head removed. In the said drawing *a* indicates the ignition plate and *f* the ignition chamber, while *h* is a neck communicating between the chamber and the vaporizing chamber A. The character *s* indicates the nozzle insertion piece which is mounted 70 in the nozzle *n* and provided with a spiral groove arranged so as to be displaceable relatively to the nozzle orifice *d*, a prolongation of the piece *s* being provided for example, at the upper end with a thread *g* and a lever *m*, so that by turning the lever *m* the piece *s* can be moved toward and away from the nozzle orifice by means of the screw thread *g*. The chamber *p* between the insertion piece and the nozzle orifice is 75 thereby enlarged or reduced and consequently in this chamber *p* a variable quantity of fuel may be collected. The fuel contained in the said chamber *p* now has a 80 whirling motion imparted to it as a result 85 of a thrust exerted by the piston of the fuel pump (not shown) which forces the fuel through the spiral threads of the piece *s*.

The fuel is thereby accelerated the amount 90 of acceleration being dependent on the quantity of fuel present in the chamber *p*, that is to say dependent on the distance of the part *s* from the orifice of the nozzle. The greater the space *p* the smaller is the acceleration and vice versa. The angle at which the 95 fuel cone is developed is however also directly dependent on the acceleration. If the fuel has a high speed of rotation the angle is greater, and vice versa the angle is 100 smaller if the fuel has a smaller speed of 110

rotation, so that when the piece *s* is screwed down and the space *p* is made small, a larger apex angle such as *a* is formed, and when the piece *s* is screwed upwardly and the space *p* is made larger, as smaller apex angle such as *B* is formed.

Claims:

1. In an internal combustion engine, an incandescent plate and a fuel admission nozzle adapted to project a cone of fuel against said plate and means to vary the apex angle of said fuel cone.
2. In an internal combustion engine, an incandescent plate and a fuel admission nozzle adapted to project a cone of fuel against said incandescent plate, said nozzle having a chamber therein and means to vary the effective volume of said chamber and thereby vary the apex angle of said fuel cone.
3. In an internal combustion engine, a fuel supplying means, a nozzle having an orifice through which the fuel is passed, an incandescent plate against which the fuel is projected and means within said nozzle to vary the density of the fuel at its points of impact with the plate without varying the quantity of fuel passing through the nozzle.
4. In an internal combustion engine, an incandescent plate, a nozzle adapted to project a fuel supply against said plate and means to regulate the density of the fuel supply at its points of contact with said plate without varying the quantity of fuel passing through said nozzle, said means comprising an adjustable member within said nozzle.
5. In an internal combustion engine, an incandescent plate, a nozzle adapted to project a fuel supply against said plate, and means to regulate the density of the fuel supply at its points of contact with said plate without varying the quantity of fuel passing through said nozzle, said means comprising an adjustable member having a plurality of spiral grooves therein adapted to give a swirling motion to said fuel within said nozzle.
6. In an internal combustion engine, an incandescent plate, a nozzle having an orifice adapted to project a fuel supply against said plate, a chamber in said nozzle and a longitudinally movable member in said chamber, said member provided with a plurality of spiral grooves and means to adjust said member to provide a variable space in said nozzle adjacent said orifice.
7. In an internal combustion engine, having a cylinder with a piston therein, a fuel admission nozzle, an incandescent plate provided with an ignition chamber, said engine being provided with a combustion chamber located between said nozzle and incandescent plate, said incandescent plate being located below said nozzle and being provided with an orifice connecting said ignition and com-

bustion chambers, said orifice being situated below and in alignment with said nozzle whereby any drops of fuel forming at the bottom of the nozzle will fall through said orifice into said ignition chamber.

70

8. In an internal combustion engine, an incandescent plate provided with an ignition chamber; a combustion chamber adjacent said plate, said plate provided with an orifice connecting said ignition and combustion chambers; and a fuel admission nozzle opposite said plate adapted to project a cone of fuel against said plate, said nozzle provided with adjustable means to vary the apex angle of said fuel cone whereby the density of the fuel supply at the plate may be varied.

75

9. A fuel admission device for use with internal combustion engines comprising a fuel nozzle means for attaching said nozzle to a cylinder head, a chamber in communication with said nozzle, means for admitting fuel to said chamber, and an insertion piece in said chamber having spiral grooves thereon adapted to be moved in said chamber, an incandescent plate, means for attaching said plate in an engine cylinder opposite the fuel nozzle, an ignition chamber in said plate and means for communicating between said ignition chamber and the interior of the cylinder head, said communicating means being arranged coaxially with the fuel nozzle.

80

10. As an article of manufacture a fuel admission device for use with an internal combustion engine comprising a cylindrical member, a piston member in said cylindrical member having spiral grooves thereon, a threaded member in threaded engagement with said cylinder, means connecting said threaded member with said piston member, means for turning said threaded member, means for admitting fuel into said cylinder between said threaded member and piston member, means for discharging fuel from said cylinder on the side of the piston member remote from the fuel inlet means and means for attaching said cylinder to the head of an engine cylinder, an incandescent plate, means for attaching said plate in an engine cylinder opposite the fuel nozzle an ignition chamber in said plate and means for communicating between said ignition chamber and the interior of the cylinder head, said communicating means being arranged coaxially with the fuel nozzle.

85

110

10. As an article of manufacture a fuel admission device for use with an internal combustion engine comprising a cylindrical member, a piston member in said cylindrical member having spiral grooves thereon, a threaded member in threaded engagement with said cylinder, means connecting said threaded member with said piston member, means for turning said threaded member, means for admitting fuel into said cylinder between said threaded member and piston member, means for discharging fuel from said cylinder on the side of the piston member remote from the fuel inlet means and means for attaching said cylinder to the head of an engine cylinder, an incandescent plate, means for attaching said plate in an engine cylinder opposite the fuel nozzle an ignition chamber in said plate and means for communicating between said ignition chamber and the interior of the cylinder head, said communicating means being arranged coaxially with the fuel nozzle.

100

115

11. An ignition arrangement for use with internal combustion engines comprising a cylinder, a vaporizing chamber in said cylinder, an ignition plate fitted to said chamber, an ignition chamber in said plate means for communicating between said ignition and vaporizing chambers, a cylindrical member arranged opposite said ignition chamber a piston member in said cylindrical member having spiral grooves thereon, a threaded member in threaded engagement with said

110

cylinder, means connecting said threaded member with the said piston member, means for turning said threaded member, means for admitting fuel into said cylinder between 5 said threaded member and piston member, means for discharging fuel from said cylinder in the side of the piston member remote from the fuel inlet means, said discharging means being arranged in axial alignment 10 with the communicating means between the vaporizing and ignition chambers.

12. As an article of manufacture a fuel admission device for use with an internal combustion engine comprising a cylindrical member, a piston member in said cylindrical member having spiral grooves thereon, a threaded member in threaded engagement 15 with said cylinder, a spindle connecting said

threaded member with said piston member, an extension of said spindle from said threaded member, a lever on said extension and means for operating said lever, means for admitting fuel into said cylinder between said threaded member and piston member, means for discharging fuel from said cylinder in the side of the piston member remote 20 from the fuel inlet means and means for attaching said cylinder to the head of an engine cylinder.

In testimony whereof I affix my signature 25 in presence of two witnesses.
